UNITED STATES PATENT OFFICE.

ARRAH J. WHISLER, OF GOSHEN, INDIANA, ASSIGNOR TO GOSHEN RUBBER WORKS, OF GOSHEN, INDIANA, A CORPORATION OF INDIANA.

DESIGN FOR RUBBER MATTING.

No. 38,238.

Specification for Design.

Patented Sept. 11, 1906.

Application filed July 25, 1906. Serial No. 327,790. Term of patent 7 years.

To all whom it may concern:

Be it known that I, ARRAH J. WHISLER, a citizen of the United States, and a resident of Goshen, in the county of Elkhart and State of Indiana, have invented a new, original, and ornamental Design for Rubber Matting, of which the following is a description, reference being had to the accompanying drawing, forming part hereof.

The figure is a plan view of a section of rubber matting, showing my new design.

I claim—

The ornamental design for rubber matting as shown.

ARRAH J. WHISLER
